(57) **CLAIM**

The ornamental design for the golf club alignment device, as shown and described.

DESCRIPTION

This application is a continuation-in-part of the non-provisional patent application to the same inventors filed under Ser. No. 16/873,412, filed on Apr. 8, 2020.

FIG. 1 is an isometric view of the golf club alignment device of this invention;

FIG. 2 is a top plan view of the invention;

FIG. 3 is a left side view;

FIG. 4 is a right side view; the back view being a mirror image thereof;

FIG. 5 is a bottom view;

FIG. 6 is a front view;

FIG. 7 is a schematic view showing a golfer utilizing a golf club including the alignment device of this invention, applied to the top of its hand grip;

FIG. 8 is an exploded view of the golf club alignment device of this invention; and,

FIG. 9 is a top view of a modified alignment device for the handle of the golf club.

The broken line showing of a human figure with golf is included for the purpose of illustrating non-claimed subject matter and forms no part of the claimed design.
